HANGER BRACKET FOR GUITARS AND THE LIKE

Thomas J. Fitzsimmons, 1708 Military Ave.,
Omaha, Nebr. 68111

Filed June 12, 1969, Ser. No. 17,681

Term of patent 14 years

Int. Cl. D8—03

U.S. Cl. D8—233

F/G. 1

F/G. 2

F/G. 3

FIG. 1 is a perspective view of a hanger bracket for guitars and the like and showing a guitar in dotted lines for illustrative purposes only;

FIG. 2 is a side elevational view; and

FIG. 3 is a rear elevational view of the bracket.

I claim:

The ornamental design for a hanger bracket for guitars and the like, as shown and described.
